RADIO TUNING INDICATOR FACE PLATE

Maurice D. Katz, 35 Broadway, Lawrence, N.Y. 11559

Filed Mar. 12, 1971, Ser. No. 123,923

Term of patent 14 years

Int. Cl. D14—03, 99

U.S. Cl. D26—1

FIG.1

FIG.2

FIG.3

FIG. 1 is a front perspective view of a radio tuning indicator face plate, with a periphery shaded border, showing my new design;

FIG. 2 is a modified embodiment of the face plate illustrated in FIG. 1; and

FIG. 3 is a front perspective view of a further modified embodiment of the face plate illustrated in FIG. 1.

The broken lines representing the radio are shown for illustrative purposes only.

I claim:

The ornamental design for a radio tuning indicator face plate, substantially as shown and described.
